UNITED STATES PATENT OFFICE.

HERBERT S. HUMPHREY, OF KALAMAZOO, MICHIGAN.

WATER-HEATER.

No. 903,863.

Specification of Letters Patent.

Patented Nov. 17, 1908.

Application filed January 10, 1908. Serial No. 410,144.

To all whom it may concern:

Be it known that I, HERBERT S. HUMPHREY, a citizen of the United States, residing at the city and county of Kalamazoo, State 5 of Michigan, have invented certain new and useful Improvements in Water-Heaters, of which the following is a specification.

This invention relates to improvements in gas burners.

10 My improved gas burner is particularly adapted and designed by me for use in water heaters, such as illustrated in my application for Letters Patent filed September 12, 1907, Serial No. 392,595, although it is desirable and adapted for use in various other relations where a heating burner is desired.

The main objects of this invention are,— First, to provide an improved gas burner for heating purposes which is of large capacity, 20 and, at the same time, one which secures a very perfect combustion of gas. Second, to provide an improved burner for water heaters and the like which is effectively protected from water dripping from above. 25 Third, to provide an improved burner in which the parts are so arranged that they do not become overheated when in use, thereby obviating to a large extent the liability of “backlighting” or “backfiring.” Fourth, to 30 provide an improved burner possessing these advantages which is very economical in structure, and is very durable in use.

Further objects, and objects relating to details of construction, will definitely appear 35 from the detailed description to follow.

I accomplish the objects of my invention by the devices and means described in the following specification.

The invention is clearly defined and 40 pointed out in the claims.

A structure embodying the features of my invention is clearly illustrated in the accompanying drawing, forming a part of this specification, in which,

45 Figure 1 is a detail view of a water heater provided with my improved burners. Fig. 2 is an enlarged detail vertical section, taken on a line corresponding to line 2—2 of Fig.

1. Fig. 3 is a plan view of the cap-plate of the burner, looking in the direction of the arrow above Fig. 2. Fig. 4 is a cross section of the burner, taken on a line corresponding to line 4—4 of Fig. 2.

50 In the drawing, the sectional views are taken looking in the direction of the little arrows at the ends of the section lines, and

similar numerals of reference refer to similar parts throughout the several views.

Referring to the drawing, 1 represents the base; 2 the burner chambers; and 3 the water coil chamber of a water heater such as I have illustrated in my application for Letters Patent hereinbefore referred to. The water coils 4 are arranged in the water coil chamber 3 above the burners. These burners 65 are grouped in the burner chamber, being preferably arranged on the gas delivery ring 5, which is supplied from a pipe, as 6.

In order to more effectively group the burners, the ring is preferably provided with 70 arms 7, part of which project inwardly and part outwardly, the gas delivery nozzles, as 8, being located on these arms.

My improved burners preferably consist of the burner tubes 9 having cross-pieces 10 75 at their lower ends, the cross-pieces being perforated to receive the delivery nozzles 8, whereby the burners are supported. The burner tubes 9 are preferably provided with upwardly contracted mixing chambers, as 80 11, at their lower ends and upwardly-expanding expansion chambers 12 at their upper ends, the upper ends of the tubes being expanded to form enlargements or delivery chambers, as 13, these delivery chambers being 85 preferably elongated.

The cap-plate 14 for the enlargement or delivery chamber 13 of the burner tube is preferably arranged in an inclined position, as is illustrated in the drawing, the plate 90 being preferably a flat plate adapted to be secured to the head by means of suitable screws, as 15. The plate 14 is provided with a plurality of jet or burner tips 16 which project laterally therefrom. These jet or 95 burner tips are preferably arranged in zig-zagged series, as clearly appears in Fig. 3. The mouths of these burner tips preferably lie in substantially vertical planes, thereby securing an overhanging lip or projection, 100 which guards the burner from water dripping from above, and also directs the jets or flames outwardly. These burner tips are arranged in an inclined position, those of the lower series projecting outwardly beyond 105 those of the upper series. The burner tips being zigzagged, permits a free passage of air to all of the tips, and also more effectively distributes the heat. The flames, by this form of burner tips, are directed 110 away from the cap-plate, so that it does not become excessively heated when the burner

is in use, and by thus arranging the burner tips, "backlighting" is largely prevented. To further guard against "backlighting", I provide a screen, as 17. This screen is 5 preferably located against the inner side of the cap-plate, it being clamped in position thereby, thus not only securing a very effective means for holding the screen, but the same is located in a desirable position as 10 well.

I have illustrated and described my improved burner in detail in the form preferred by me on account of its structural simplicity and economy, and its effectiveness 15 in use. I am aware, however, that it may be very considerably varied in structural details without departing from my invention, and still produce a satisfactory structure, and I desire to be understood as claiming 20 the invention in the embodiment illustrated as well as broadly. It is desired to remark in this connection that in practice the mouth of the burner must be made a proper size to correspond with the amount of gas delivered by the gas delivery nozzle, and the 25 mixing tube must correspond or be properly proportioned.

Having thus described my invention, what I claim as new and desire to secure by Letters Patent is:

1. An upright burner comprising a burner tube having an enlargement or head at its upper end; an inclined cap-plate therefor, said cap-plate being provided with a plurality of laterally-projecting jet or burner tips arranged in zigzagged series, the delivery openings or mouths of said tips being in substantially vertical planes; and a screen arranged across said head beneath said cap-plate and clamped in position thereby.

2. An upright burner comprising a burner tube having an enlargement or head at its upper end; and an inclined cap-plate therefor, said cap-plate being provided with a plurality of laterally-projecting jet or burner tips arranged in zigzagged series, the delivery openings or mouths of said tips being in substantially vertical planes.

3. An upright burner comprising a burner tube having an enlargement or head at its upper end; an inclined cap-plate therefor, said cap-plate being provided with a plurality of laterally-projecting tubular jet or burner tips, the delivery openings or mouths

of said tips being in substantially vertical 55 planes; and a screen arranged across said head beneath said cap-plate and clamped in position thereby.

4. An upright burner comprising a burner tube having an enlargement or head at its 60 upper end; an inclined cap-plate therefor, said cap-plate being provided with a plurality of laterally-projecting tubular jet or burner tips, the delivery openings or mouths of said tips being in substantially vertical 65 planes.

5. A burner comprising a burner tube; a cap-plate therefor, said plate being inclined to the longitudinal axis of said burner tube and having a plurality of laterally-projecting 70 jet or burner tips arranged in a zig-zagged series, the delivery openings or mouths of said tips being in substantially vertical planes; and a screen arranged against the inside of said cap plate.

6. A burner comprising a burner tube; and a cap plate therefor, said plate being inclined to the longitudinal axis of said burner tube and having a plurality of separated projecting jet or burner tips arranged in a 80 zigzagged series, to permit the circulation of air around the same; the delivery openings or mouths of said tips being in substantially vertical planes.

7. A burner comprising a burner tube; a 85 cap plate therefor, said plate being inclined to the longitudinal axis of said burner tube and having a plurality of projecting tubular jet or burner tips, the delivery openings or mouths of said tips being in substantially 90 vertical planes; and a screen arranged against the inside of said cap plate.

8. A burner comprising a burner tube; and a cap plate therefor, said plate being inclined to the longitudinal axis of said burner 95 tube and having a plurality of separated projecting tubular jet or burner tips, arranged to permit free circulation of air around the same; the delivery openings or mouths of said tips being in substantially 100 vertical planes.

In witness whereof, I have hereunto set my hand and seal in the presence of two witnesses.

HERBERT S. HUMPHREY. [L. S.]
